Patented Feb. 6, 1923.

UNITED STATES PATENT OFFICE.

WILLIAM JEPSON, OF BARNSBURY, LONDON, ENGLAND.

WASHING MACHINE.

Application filed July 14, 1921. Serial No. 484,721.

To all whom it may concern:

Be it known that I, WILLIAM JEPSON, a British subject, residing at 47 Lofting Road, Barnsbury, London, England, have invented 5 certain new and useful Improvements in Washing Machines (for which I have filed application in England, May 27, 1920, Patent No. 14,505), of which the following is a specification.

10 This invention relates to washing machines having circular rotary cages adapted to be rotated alternately in opposite directions. Such machines have already been provided with internal beaters in the form 15 of longitudinal ribs or projections of various shapes adapted to operate upon the materials being washed during rotation.

The present invention primarily consists 20 in a washing machine having a cage whereof the circumferential wall is shaped to form one or more longitudinal combined internal beaters and external perforated troughs, the latter being adapted to raise to a predetermined height a charge of water externally 25 to the cylinder and cause it to be discharged through its perforations on to the materials being washed within the cylinder. It further consists in a precise form and arrangement of such combined beater and water 30 trough which I have found to possess considerable advantages over and above those functions which are solely attributable to the mere combination.

The combined beater and trough are preferably formed by shaping a single plate of metal forming part of the wall of the cage so that outwardly it forms two troughs and inwardly it forms two beaters.

The preferred form of the invention is 40 illustrated in the accompanying drawing in which Fig. 1 illustrates an elevational view and Fig. 2 a sectional view.

Referring now to the drawing, the combined troughs and beaters *a* are formed in 45 opposed pairs, each pair being preferably formed from a single metal plate *b'*, *b''*, *b'''* united at its edges to the cylindrical parts *h* of the rotating cage. The remote walls *c* of each pair of troughs are preferably set 50 in planes passing through the axis of the cylinder, but the near walls *d* form an angle therewith and approach each other so as to form in conjunction with the intervening part *e* of the cage wall which lies on the normal cylindrical circumference, an internal 55 pocket *f* within the cage which is adapted

to receive the charge of material to be washed and cause it to be raised, as the cage rotates, to a point whence it falls on to the near beater *a* of the following pair. At this 60 point, as the beater is moving in a sense opposite to the direction of fall, the charge is beaten and rolled over into the succeeding pocket, when the process is repeated.

The walls *d* and intervening part *e* of each 65 system are freely perforated, the perforations being partly indicated in Fig. 1 by centring only; and extensions *g* of the cylindrical portions *h* extend partly over the troughs *l* from the walls *c* in each case to 70 ensure that a substantial charge of water is raised by the troughs above the level of the water in the machine. This charge of water, as the troughs are raised, falls through the perforations in the walls *d* on 75 to the material in the cage, a certain quantity being directed on to the said material as it falls from the rising pocket *f* on to the lower beaters, and this combines with the operation described above to produce a 80 very efficient cleansing of the material. It will be understood that of each pair of troughs, one functions as the cage rotates in a clockwise sense and the other as the cage rotates in a counter-clockwise sense. In 85 the drawing *k* represents a central portion, *l* parts of an end plate, and *o* a hinged door.

The number of troughs and pockets and precise configuration thereof may be varied 90 according to the size and speed of the machine; but it is desirable that as the material falls from a pocket as the latter becomes inverted, the inclined wall from which it slides should be set at such an angle as to throw the material on to the near upturned 95 beater of the following pair, when the rotation of the machine delivers it at once into the corresponding pocket. The near walls of a pair of troughs and intervening cylindrical portion of the shell may be shaped to 100 form a continuous curve if desired.

In the form shown, I have illustrated three 105 pairs of troughs and beaters as I find that this produces the most satisfactory results with the usual size and speed of running of the machine.

I claim:—

1. In a washing machine, a cage adapted 110 for alternating rotary movement, the wall of said cage being made up in part of independent sections, each formed to provide two hollow trough-like beaters opening exter-

only of the trough and having a short straight wall substantially radial of the cage and a long straight wall at an angle to the short wall, the long wall being 5 perforated throughout its area and projected at such an angle to the radial line of the cage that its continuation would intersect the short wall of the immediately adjacent beater of the next section, whereby the material 10 lifted between the beaters of one section will in delivery from said section by gravity during movement of the cage be directed by the long wall of one beater of such section onto the point formed by the long and short 15 walls of the following beater of the adjacent section.

2. In a washing machine, a cylindrical cage adapted for alternating rotary movement, the wall of the cage being made up in 20 part of three independent sections, each formed to provide two hollow trough-like beaters having a short wall substantially

radial of the cage and a long wall at an angle to the short wall, the beaters of each section having the long walls adjacent each other with that portion of the section intermediate the relatively outer ends of the said long walls disposed in the plane of the wall of the cage, the angle of each long wall being at such an angle to the radial line of the 30 cage that if continued it would intersect the short wall of the following beater inwardly of the inner end thereof, the long walls and intermediate curved portion of each section forming a pocket having divergent straight 35 walls, one of which according to the direction of rotation acts as a guide for the clothes falling from such pocket to direct the clothes onto the point formed by the short wall and long wall of the following 40 beater section in the direction of rotation.

In testimony whereof I affix my signature.

WILLIAM JEPSON.
